DISPENSING APPARATUS

Paul B. Renfrew, Fort Wayne, Ind., assignor to
 S. F. Bowser & Company, Inc., Fort Wayne,
 Ind., a corporation of Indiana

Application April 10, 1930. Serial No. 443,226

32 Claims. (Cl. 221—67)

My invention relates to dispensing apparatus particularly adapted to the dispensing of lubricating oils of various grades and qualities although it may have a general application, and one of the objects of my invention is the provision of an improved and efficient structure of this type well adapted for use outdoors during cold weather.

A further object of the invention is the provision of means to provide air circulation in dispensing apparatus.

Another object of the invention is the provision of improved and efficient heating means for dispensing apparatus.

A further object of the invention is the provision of drip cup receiving means for dispensing apparatus, combined with mechanism for locking such drip receiving means into such position as to prevent the operation of the dispensing apparatus.

A further object of the invention is the provision of visible dispensing apparatus, combined with means for providing circulation of air and maintaining visibility.

Other objects of the invention will appear hereinafter, the novel features and combinations being set forth in the appended claims.

In the accompanying drawings—

Fig. 1 is a sectional elevation of an oil fountain embodying my improvements;

Fig. 2 is a horizontal sectional view taken on the line 2—2 of Fig. 1 looking upwardly as indicated by the arrows;

Fig. 3 is a sectional elevation taken on the line 3—3 of Fig. 2 looking in the direction of the arrows and showing the upper visible portion of the fountain shown in Fig. 1;

Fig. 4 is a wiring diagram to illustrate the control of the heating elements embodied in the structure shown in Fig. 1;

Fig. 5 is a plan view of the drip receiving means with the drip cups omitted; and

Fig. 6 is a sectional elevation of the canopy with the plate of Fig. 5 locked thereto.

In Fig. 1 is shown a base 7 on which is mounted a housing 8 lined with asbestos 9. On top of the housing 8 is mounted the basin 10 which is provided with the chamber 11 surrounding the central tubular support 12.

Extending from the upper central portion of the support 12 is another tubular support 13 of smaller diameter than the support 12. At the upper end of the tubular support 13 is a circular seat 14 for the glass cylinder 15. As shown in Fig. 3, the lower end of the glass cylinder 15

may be hermetically sealed from the tubular support 13 by means of the cork washer 16 and the litharge applied at 17.

Surmounting the glass cylinder 15 is the canopy 18. The upper end of the cylinder 15 may be hermetically sealed from the canopy 18 in the same manner as the lower end is hermetically sealed from the support 13.

Extending through the central portion of the base 7 into the housing 8 is a plurality of oil supply pipes 19. In the structure shown four such supply pipes are included, one for each of the four glass tubes shown at 20, 21, 22 and 23 in Fig. 2.

The upper ends of the tubes 20, 21, 22 and 23 are connected to oil delivering passageways under the canopy 18. For the sake of more clearly illustrating the structure a section of Fig. 1 is taken from the front diagonally at 45° to the center and then horizontally toward the right. The passageway in the canopy 18 for the tube 20 is shown at 24 in Fig. 1. The casting 25 which has therein the oil duct or passageway 24 may be integral with or rigidly secured to the canopy 18. To the discharge end of the oil duct 24 is connected a nozzle 26 having a valve controlled by the manually operated device 27. The nozzle assembly 28 may be secured to the casting 25 by means of the bolt 29. In a similar manner the bolts 30 may be relied on to clamp the union 31 to the bottom of the tube 20. The union 31 may be integral with the casting 13, 14. The pipe 19 shown at the left of Fig. 1 may be connected to the union 31. It will thus be seen that when air pressure is exerted on a supply of oil in a distant tank connected under ground to the pipe 19, the opening of the nozzle 26 by means of the handle 27 will permit oil to be dispensed into a container held beneath the nozzle.

Within the space between the four transparent oil tubes 20, 21, 22 and 23 is located an electric lamp 32 preferably extending the full length of the tubes as shown in Fig. 1. Between each oil tube and the next adjacent one is an opaque guard plate held in place by a vertical rod. Between the oil tubes 20 and 21 is a guard plate 33 held in place by the rod 34. Similar guard plates are shown at 35 and 36 held in place by the rods 37 and 38 respectively. Between the oil tubes 22 and 23 is the electric conduit 39 with strips of opaque material bent back on themselves between the pipe 39 and the tubes 22 and 23 as shown at 40 and 41 in Fig. 2. Therefore when the current is turned on the

electric lamp 32 the light therefrom will be obstructed by the guard plates 33, 35 and 36 and by the opaque pipe 39 and the opaque fillers 40 and 41. The oil tubes 20, 21, 22 and 23 are always full of oil. A plurality of tubes are useful for the purpose of serving different grades and qualities of motor oil and it is desirable to have the illumination extend through the oil in the transparent tubes so that the oil in these tubes will be clearly visible individually without being confused with the oil in the other oil tubes.

Within the housing is an auxiliary housing 42 surrounding the supply pipes 19. The lower end of the auxiliary housing 42 opens into the chamber 43 in the housing 8 but the upper end is connected to the lower end of the tube 44 which is spaced from the inner wall of the tubular support 13 to afford an annular chamber 45. It should be understood that the upper end of the tube 44 communicates with the bottom of the chamber 46 which is formed by the vertical guard plates which engage the sides of the oil tubes 20, 21, 22 and 23 as shown in Fig. 2.

Within the auxiliary housing 42 are mounted two separate electric heating elements 47 and 48 by being connected by means of the clamps 49 and 50 to the pipes 19. The lower electric terminal for the heating element 47 is shown at 51. The terminals for the heating element 48 are shown at 52 and 53 in Fig. 1.

In Fig. 4 is shown a wiring diagram of the electric circuits and connections for the incandescent lamp 32 and the two heating elements 47 and 48. When the main line switch 54 is closed the supply mains 55 are connected to the wires which may be led underground from the building at a filling station to the oil fountain located distant therefrom in a convenient position for use and service to motor cars. The wire 56 may lead underground directly from such building to the conduit 39 leading upwardly through the base 7 and the housing 8 to the junction box 57 and thence directly to one terminal of the incandescent lamp 32 and to one terminal 51 of the heating element 47 and one terminal 52 of the heating element 48. In the other circuits 58, 59 and 60 which also lead directly from such building underground to the oil fountain and to the junction box therein there may be located manually operated switches 61, 62 and 63. The conductor 58 is connected to the lamp 32 and therefore when the switch 61 is closed the lamp 32 will be lighted up. When the switch 62 is closed the heating element 47 will be operated. The circuit for the heating element 47 may be traced from the switch 54 through the conductor 56, junction box 57, terminal 51, resistance of the heating element 47, conductor 59, switch 62, back to the other side of the switch 54. When the switch 63 is closed the heating element 48 will be operated, the circuit being through conductor 56, junction box 57, terminal 52, resistance of heating element 48, terminal 53, conductor 60 and switch 63 to the other side of the supply mains 55.

When the electric lamp 32 alone is operated the heat produced thereby may be sufficient in inclement weather to produce a circulation of air from the lower open end of the auxiliary housing 42 through the tube 44 and thence through the passageway 46 to the chamber 64 in the canopy 18. The air will then pass downwardly through the openings 65 into the passageway 66 which surrounds the oil tubes as shown in Fig. 2. The tube 44 being spaced from

the interior wall of the tube 13 the air will continue downwardly through the passageway 45 into the chamber 43 of the housing 8 and thence back into the bottom of the auxiliary housing 42. When in addition to the lamp 32 being lighted up, the switch 62 is operated to turn on the heating element 47, greater heat will be produced to keep the oil in the pipes 19 and the oil tubes 20, 21, 22 and 23 sufficiently warm to decrease the viscosity to permit free flow. In the coldest weather the heating element 48 may be turned on by means of the switch 63 in addition to the heating element 47 and the lamp 32. During the day it may not be desirable to turn on the lamp 32 and regulation of the temperature of the oil may be secured by means of the switches 62 and 63. Even without the use of the lamp 32 and/or the heating units 32, 42 and 48, the arrangement of the associated elements of my pedestal and especially the arrangement of the inner tube 42 connecting with the glass containers 20 and the concentrically surrounding transparent cylinder 15 providing inner and outer passageways, it must be apparent that a natural circulation will be provided so that in cold weather the hotter air enclosed by the more protected or lower portions of the pedestal will rise upwardly through tube 42 and will circulate through the space between the glass containers 20 and will pass upwardly and upon being chilled will thence pass downwardly through the aperture 65 and through the space between the outer glass cylinder 15 and the ring of glass containers, and thence downwardly into the base of the pedestal again, recirculating in a natural manner. Obviously when either the lamp 32 is used or the heater or both, this air-circulation is considerably augmented. In any event the glass cylinder 15 and the inner glass containers are kept clear so that the oil in the containers 20 is visible upon the outside. This arrangement of containers and outer cylinders, including the provision of a natural circulation in and about the glass cylinders and through the outer cylinder, is of great advantage.

In order to retain as much as possible of the heat which has been generated and to provide insulation against cold from the outside, the oil pipes in the base 7 are packed with rock wool 67 and the canopy 18 is packed with rock wool 68. Other insulation, preferably of a fibrous nature, may be substituted for the rock wool. The housing 8 is lined with asbestos 9. The glass cylinder 15 not only provides the outer passageway 66 but also assists in serving as an insulation against cold from the outside entering the vertical oil tubes. That is to say, the large display glass cylinder 15 in which the smaller display oil tubes are located completes the protection of warm air circulation from outside temperatures during its entire progress through the fountain.

Attached to the lower end of the tube 44 are radial brackets 69 in which is mounted a wire basket 70 for containing calcium chloride 71 for the purpose of removing all moisture from the air which flows down through the passageway 45 into the chamber 43 in the lower housing 8. The removal of the moisture from the atmosphere within the dispensing unit further increases the efficiency of the heating units 32, 47 and 48 and prevents the accumulation of moisture within the large glass display cylinder 15 and on the outer surfaces of the oil display tubes 20, 21, 22 and 23. At the periphery of

the basin 10 is a ledge or seat 72 for receiving the grid plate 73 when in its lowermost position. As shown in Fig. 5, this grid plate is provided with a large circular opening 74 in its center of sufficiently large diameter to have ample clearance when lifted over the upper edge of the tube 13 and below the casting 75 within the canopy 18. The grid plate 73 is also provided with a plurality of perforations 76 to permit such oil as may be spilled to flow back into the basin 10. Accumulated oil in the basin 10 may be removed by withdrawing the screw-threaded plug 77 shown in Fig. 1.

The grid plate 73 is also provided with a plurality of openings 78 each having a peripheral seat 79 for receiving the upper peripheral flange 80 of the drip cup 81. There are four drip cups provided for the four openings 78 in the construction shown. Each of these drip cups is separately and independently removable from the grid plate 73 for the purpose of separately emptying the drip cups, or each cup may have a drain hole in its bottom.

When the grid plate 73 together with the four drip cups 81 suspended therefrom are lifted with the central circular opening 74 moving over the tube 13 and over the lower end of the casting 75, the grid plate 73 may be tilted so as to enable one side thereof to be placed over the lug 82 on the inner side of the canopy 18 as shown in Fig. 1 and also in Fig. 6. On the opposite side of the canopy 18 as shown in Fig. 6 is located a hasp 83 over which the opening 84 in the grid plate 73 may extend so that a padlock 85 may be used to lock the grid plate in its uppermost position with the drip cups 81 covering the four dispensing nozzles as well as the handles for operating the valves connected to the nozzles. In other words, the locking of the grid plate together with the drip cups in uppermost position renders the nozzles and the nozzle control devices inaccessible and prevents operation by unauthorized persons.

The canopy 18 may be removably mounted on top of the dispensing unit so that inspection of the insulating material 68 may be had and replenishment thereof made, if desired. The lamp 32 may also be renewed. For this purpose the casting 75 may be made separate from the canopy 18 and mounted directly on the glass cylinder 15. The cap plate 86 may be used to clamp the casting 75 to the top of the glass cylinder 15 by co-action with nut 87 on the conduit 39. The canopy 18 may be secured to the cap 86 by means of the cap screw 88. The oil conduits 25 may each be separate and independent of the casting 75 and the conduits 25 may be separately secured to the tops of the oil tubes by means of the tie rods 30. The packing 60 of the insulating material 68 may be made more effective by providing the vertical walls 89 and 90, the latter being secured to the casting 25 as shown at 91 in Fig. 1; 91 designates also a manually operated valve for removing entrapped air in the oil duct 24.

An electric light socket may also be provided at 92 for an electric lamp connected in parallel with the one designated 32. The electric fixtures for the sockets 92 and 93 are connected rigidly to the upper central portion of the canopy 18. By means of the spaced set screws 94 the canopy may be leveled and long electric light bulb 32 may be centralized within the chamber 46 between the various oil tubes 20, 21, 22 and 23, 75 and after this has been done the canopy may

be rigidly connected to the cap 86 by means of the cap screw 88.

It should be particularly noted that the various grades of oil are always on display since the supply tubes 19 and the transparent tubes 20, 21, 22 and 23 are always maintained full of oil. The electric heating and air circulation arrangement is for the purpose of maintaining the oil of such consistency as to flow freely when the oil fountain is located outside distant from a filling station building. The serving of the oils is therefore centralized at one convenient point where the oil fountain unit is located.

Obviously those skilled in the art may make various changes in the details and arrangement of parts without departing from the spirit and scope of the invention as defined by the claims hereto appended and I wish therefore not to be restricted to the precise construction herein disclosed.

Having thus fully disclosed an embodiment of my invention, what I desire to secure by Letters Patent of the United States is:

1. In liquid dispensing apparatus, the combination with a hollow pedestal forming a chamber, of a plurality of liquid supply pipes extending through the chamber in said pedestal, a housing within said chamber surrounding said supply pipes and open at the bottom, heating means within said housing adjacent said pipes, 105 means comprising valve controlled nozzles for dispensing liquids from said pipes, and means affording a circulation of air from the interior of said housing upwardly and thence downwardly outside of said housing into the chamber in 110 said pedestal to the lower open end of said housing.

2. In a dispensing apparatus, the combination of a support, of dispensing means mounted thereon and including a conduit through which liquid to be dispensed is adapted to flow, an enclosure for said conduit surrounding and in spaced relation therefrom, and means associated with said conduit and said enclosure providing means for effecting circulation of air about substantially the entire periphery of said conduit.

3. In a dispensing apparatus, the combination of a support, of dispensing means mounted in said support and comprising a transparent conduit through which liquid is adapted to flow, a 125 transparent enclosure spaced from and surrounding said conduit, and means associated with said conduit and said enclosure for providing upwardly and downwardly extending and constantly open air passageways for the circulation of air about the exterior periphery of said conduit.

4. In dispensing apparatus, the combination with a support, of a plurality of supply pipes extending upwardly through said support, a 135 plurality of transparent conduit tubes one connected to each of said supply pipes, a plurality of valve controlled nozzles one connected to each of said transparent conduits, and a transparent cylinder spaced from and surrounding said 140 plurality of transparent conduits to provide an air passageway along at least a portion of the exterior wall of said conduits.

5. In dispensing apparatus, the combination with a support, of a plurality of spaced-apart 145 transparent conduits mounted on said support, delivery nozzles connected to the upper ends of said transparent conduits, supply pipes connected to the lower ends of said transparent conduits, a source of illumination extending 150

- along the space between said conduits, and opaque guards between the next adjacent transparent conduits to cut off the illumination except through said transparent conduits, said guards and said transparent conduits providing an air-circulating conduit and means for circulating air therethrough.
6. In dispensing apparatus, the combination with a support, of dispensing means mounted thereon comprising a plurality of vertical transparent conduits, a source of illumination in the space between said conduits, an enclosure for said conduits and spaced therefrom, and means between adjacent conduits to co-act with said transparent tubes to form closed walls for the space between the conduits to provide an air-circulating shaft and means for circulating air through said shaft.
7. In dispensing apparatus, the combination with a pedestal having a closed compartment, of dispensing means mounted thereon and comprising a plurality of transparent conduits forming inner and outer air-circulating passages, a plurality of supply pipes extending through said pedestal to said conduits, a tubular enclosure for said pipes open at its lower end into said compartment and open at its upper end into the space between said tubular conduits, a transparent enclosure surrounding said conduits and spaced therefrom, a tubular connection between the bottom of said enclosure and the compartment in said housing, and heating means for inducing circulation of air upwardly from the bottom of said first-named tubular enclosure into the space between said conduits and thence downwardly back into said compartment.
8. In dispensing apparatus, the combination with a support, of dispensing means mounted thereon, a canopy for the upper portion of said dispensing means, removable drip receiving means on said support, and means for locking said drip receiving means to said canopy to render inoperative the dispensing means.
9. In dispensing apparatus, the combination with a support, of dispensing means mounted thereon comprising a plurality of nozzles, drip receiving means shiftable to another position to prevent dispensing from said nozzle mounted on said support and comprising a plurality of drip cups, and means for locking the drip receiving means with said cups over said nozzles to render the latter inaccessible and thereby prevent the operation of the dispensing means.
10. In dispensing apparatus, the combination with a support, of dispensing means mounted thereon and comprising a plurality of valve controlled dispensing nozzles, a canopy for the top of said dispensing means, drip receiving means removably mounted on said support and comprising a plurality of drip cups one for each of said nozzles, and means for locking the drip receiving means to the bottom of said canopy with the said drip cups respectively covering said nozzles to render the same inaccessible and prevent the operation of said dispensing means.
11. In dispensing apparatus, the combination with a pedestal, of dispensing means mounted thereon and comprising a plurality of spaced-apart dispensing nozzles, a removable plate mounted on top of said pedestal to serve as a shelf for receptacles to receive liquid from said nozzles, drip cups supported by said plate, and means for locking said plate in an elevated position with said drip cups over said nozzles to render the same inaccessible and thereby prevent the operation of the dispensing means.
12. An oil fountain comprising an upstanding base, a head mounted on the top of said base, and comprising a transparent cylinder and a plurality of transparent containers mounted within said cylinder for holding oil or other fluid, means for delivering fluid to each of said containers, and a canopy mounted at the top of said transparent cylinder and having overlying portions, a plurality of nozzles depending from the under side of said overlying portions and being disposed outside of the circumferential plane of the transparent cylinder, means forming separate passages in the canopy from the tops of said containers to the separate nozzles, valve means for controlling the discharge from each nozzle. 80
13. An oil fountain comprising an upstanding pedestal having a head projecting upwardly therefrom, said head comprising a transparent hollow member, a plurality of transparent containers disposed within said hollow transparent member, means for conducting liquid into each of said containers, said head being provided at 85 its top and above said transparent cylinder and containers with a canopy, a plurality of nozzles depending from said head, means connecting each nozzle with a container, and control means for dispensing liquid from each nozzle. 90
14. An oil fountain comprising an upstanding pedestal having a head projecting upwardly from and centrally of said basin, a plurality of fluid containers mounted in said head, a canopy at 95 the top of said head, a plurality of spaced-apart nozzles located directly over said drip basin, said drip basin being vertically movable and having means adapted to mask said nozzles. 100
15. An oil fountain comprising an upstanding pedestal, provided at its top with an outstanding substantially horizontally arranged drip basin, a head projecting upwardly from and centrally of said basin, a plurality of fluid containers mounted in said head, a canopy at 105 the top of said head, a plurality of spaced-apart depending nozzles located directly over said drip basin, means for operating each nozzle, said drip basin being vertically shiftable and having means to prevent the operation of said nozzle operating 110 means.
16. An oil fountain comprising an upstanding pedestal, provided at its top with an outstanding substantially horizontally arranged drip basin, a head projecting upwardly from and 120 centrally of said basin, a plurality of fluid containers mounted in said head, a canopy at the top of said head, a plurality of spaced-apart depending nozzles located directly over said drip basin, means for operating each nozzle, said drip basin being vertically shiftable and having means 125 adapted to interlock with said canopy and to prevent the operation of said nozzle operating means, and means for detachably locking said drip basin in such interlocked position. 130
17. An oil fountain comprising a pedestal, a head mounted in the top of said pedestal and terminating in a canopy, a drip basin mounted at the bottom of said head, said drip basin extending outwardly from said head, a plurality of depending discharge nozzles located directly 135 over said drip basin and concentrically about said head, means for discharging fluid from each of said nozzles, and a grid normally resting on said drip basin to provide a support for 140
18. An oil fountain comprising a pedestal, a head mounted in the top of said pedestal and terminating in a canopy, a drip basin mounted at the bottom of said head, said drip basin extending outwardly from said head, a plurality of depending discharge nozzles located directly 145 over said drip basin and concentrically about said head, means for discharging fluid from each of said nozzles, and a grid normally resting on said drip basin to provide a support for 150

- containers adapted to receive fluid from said discharge nozzle, said grid being shiftable with respect to said nozzles, and having means to prevent the operation of said fluid discharge means when in one shifted position. 5
18. In a fluid vending and display fountain of the character described, the combination of a pedestal having a display head mounted on its top, said display head including a transparent cylinder and a plurality of transparent containers mounted within said cylinder in spaced relation therefrom, means for admitting and discharging fluid into each of said containers, and means associated with said cylinder and said containers for providing a flow of air through the space between said cylinder and said containers. 10
19. In a fluid vending and display fountain of the character described, the combination of a pedestal having a display head mounted on its top, said display head including a transparent cylinder and a plurality of transparent containers mounted within said cylinder in spaced relation therefrom, means for admitting and discharging fluid into each of said containers, and means associated with said cylinder and said containers for providing a circulation of air through the space between said cylinder and said containers and between said containers. 15
20. In a fluid vending and display fountain of the character described, the combination of a pedestal having a display head mounted on its top, said display head including a transparent cylinder and a plurality of transparent containers mounted within said cylinder in spaced relation therefrom, means for admitting and discharging fluid into each of said containers, and means for providing a natural flow of air in continuous circulation in series across the inner and outer walls of the transparent containers. 20
21. In a fluid vending and display fountain of the character described, the combination of a pedestal having a display head mounted on its top, said display head including a transparent cylinder and a plurality of transparent containers mounted within said cylinder in spaced relation therefrom, means for admitting and discharging fluid into each of said containers, and means associated with said pedestal, said cylinder and said containers, for causing a continuous circulation of air in series across the inner walls of said glass containers, and past the inner wall of said transparent cylinder. 25
22. In a fluid vending and display fountain of the character described, the combination of a pedestal providing a seat on its upper portion, a glass cylinder detachably mounted on said seat, a canopy detachably mounted on the top of said glass cylinder, means for holding said canopy and glass cylinder in assembled relation on said seat, a plurality of fluid supply pipes disposed within said pedestal and terminating near the base of the glass cylinder, a plurality of seats, a glass container detachably mounted upon and in fluid-tight relation with each seat, means forming a cap for each glass container, and providing a discharge passage from each glass container, and means for controlling the flow of fluid from each said passage. 30
23. A dispensing apparatus having a liquid dispensing nozzle, a drip-receiving member movably mounted on said apparatus, and shiftable from drip-receiving position into a position to prevent the dispensing of liquid from said nozzle. 35
24. In a liquid dispensing apparatus, a support, a dispensing nozzle thereon, a drip chamber on said support beneath said nozzle, means associated with said chamber for withdrawing accumulated drip liquid therefrom, means adapted to be supported on said chamber and including a drip cup adapted to catch the drip from the nozzle, said means being shiftable to a position on the support to prevent the dispensing of liquid from the nozzle. 80
25. In a liquid dispensing apparatus, the combination of an upstanding support, a liquid dispensing nozzle carried thereby, a valve control for said nozzle, a drip receiving member shiftably mounted on said support and movable from a position adapted to catch the drip from said nozzle to a position preventing the operation of said nozzle control. 85
26. In a liquid dispensing apparatus, the combination of an upstanding support, a liquid dispensing nozzle carried thereby, a valve for said nozzle, a drip receiving member shiftably mounted on said support and movable from a position adapted to catch the drip from said nozzle to a position preventing the operation of said nozzle valve and means for locking the drip-receiving member in said latter position. 90
27. In an oil dispensing unit, the combination of a support provided with a plurality of depending nozzles adapted to dispense oil therefrom, a control member for each nozzle, and a drip cup holder adapted to be supported on said unit beneath said nozzle and shiftable relative to said support to prevent the operation of any of said nozzle-controlling members. 105
28. In an oil dispensing fountain, the combination of an upstanding support provided with a depending nozzle, a drip basin mounted on said support immediately beneath said nozzle to catch the drip therefrom, a perforated grill adapted to rest in one position over said basin, said grill detachably carrying a plurality of cups each mounted directly under the drip of a nozzle, said grill and cups being shiftable upwardly to enclose said nozzles, and means for locking said grill in an enclosing position. 115
29. In an oil dispensing fountain, the combination of an upstanding tower provided with a depending liquid dispensing nozzle, a drip-receiving member located below said nozzle to catch the drip therefrom, a member shiftably mounted on said tower, a cup detachably carried by said member, and means for locking said cup and member in position relative to said nozzle to prevent the dispensing of liquid from said nozzle and to lock the cup from being removed from said member. 125
30. In an oil dispensing tower, the combination with an upstanding support provided with a central portion and provided at its top with a plurality of depending liquid nozzles, means passing through said central portion for passing liquid to said nozzles, a drip-receiving member carried by said support in position directly under said nozzles to receive the drip therefrom, a grill having a central opening surrounding said central portion and permitting the free vertical sliding of said grill relative to said central portion, said grill having a plurality of apertures for the reception of cups whereby each cup is held directly under a nozzle to catch the drip therefrom, the upper portion of said tower having means for locking the grill in position relatively to said nozzle whereby said cups will enclose said nozzles when so locked. 135
31. In an oil dispensing tower, the combination with an upstanding support provided with a central portion and provided at its top with a plurality of depending liquid nozzles, means passing through said central portion for passing liquid to said nozzles, a drip-receiving member carried by said support in position directly under said nozzles to receive the drip therefrom, a grill having a central opening surrounding said central portion and permitting the free vertical sliding of said grill relative to said central portion, said grill having a plurality of apertures for the reception of cups whereby each cup is held directly under a nozzle to catch the drip therefrom, the upper portion of said tower having means for locking the grill in position relatively to said nozzle whereby said cups will enclose said nozzles when so locked. 140
32. In an oil dispensing tower, the combination with an upstanding support provided with a central portion and provided at its top with a plurality of depending liquid nozzles, means passing through said central portion for passing liquid to said nozzles, a drip-receiving member carried by said support in position directly under said nozzles to receive the drip therefrom, a grill having a central opening surrounding said central portion and permitting the free vertical sliding of said grill relative to said central portion, said grill having a plurality of apertures for the reception of cups whereby each cup is held directly under a nozzle to catch the drip therefrom, the upper portion of said tower having means for locking the grill in position relatively to said nozzle whereby said cups will enclose said nozzles when so locked. 145
33. In an oil dispensing tower, the combination with an upstanding support provided with a central portion and provided at its top with a plurality of depending liquid nozzles, means passing through said central portion for passing liquid to said nozzles, a drip-receiving member carried by said support in position directly under said nozzles to receive the drip therefrom, a grill having a central opening surrounding said central portion and permitting the free vertical sliding of said grill relative to said central portion, said grill having a plurality of apertures for the reception of cups whereby each cup is held directly under a nozzle to catch the drip therefrom, the upper portion of said tower having means for locking the grill in position relatively to said nozzle whereby said cups will enclose said nozzles when so locked. 150

31. In a dispensing apparatus, the combination with a support, a dispensing mechanism comprising a plurality of vertical, transparent conduits mounted in spaced relation, a source of illumination in the space between said conduits, guards between adjacent conduits to cut off the illumination except through said transparent conduits, said guards cooperating with the exterior walls of said conduits to provide an air circulating passage concentrically within said conduits, and a transparent cylinder surrounding and spaced from said conduits, and means for causing a circulation of air through said passages.

32. In a dispensing apparatus, the combination of a support, of dispensing means mounted therein comprising a transparent conduit through which liquid is adapted to flow, means enclosing at least a part of said conduit, and spaced therefrom to provide an air passageway disposed about at least a portion of the exterior surface of said conduit, a part of said enclosing means being transparent, and means associated with said conduit and said enclosing means for providing a circulation of air through said passageway.
